SHOE SPIKE

Alfred G. Merlin, Cleveland, Ohio

Application December 2, 1949, Serial No. 130,643

1 Claim. (Cl. 36—59)

1. *Introduction*

The invention relates to spikes or calks for shoes and particularly to an integral metal article of this character suitable for shoes used for athletic purposes, such as golf shoes.

The objects of the invention are to provide an article of the character stated which can be economically manufactured and thus sold at a reasonable price, which can be readily and conveniently securely applied to the shoe, which will remain securely fastened even though the leather to which it is applied expands and shrinks, and which will readily pierce the ground of hard golf fairways and thus reduce slippage to a minimum.

The annexed drawing and the following description set forth in detail certain means illustrating the improvements in shoe spikes, the same presenting, however, only a few of the various forms in which the principle of the invention may be embodied.

In said annexed drawing:

Figure 1 is a bottom plan of a shoe showing a plurality of the improved metal spikes applied to the sole and heel thereof:

Figure 2 is a fragmentary elevation, upon an enlarged scale, of a shoe, showing the heel thereof in transverse section, to which heel one of the improved spikes has been applied and another spike is being applied.

Figure 3 is an exploded view, upon an enlarged scale, showing the improved spike in elevation with a loose washer therefor in section, and a nut member which is embedded in the shoe sole or heel and forms a retaining member for the spike;

Figure 4 is a bottom plan of the retaining member which is embedded in the shoe sole or heel, the figure being taken from the plane of the line 4-4, Figure 3;

Figure 5 is a bottom plan of the metal spike, the figure being taken from the plane indicated by the line 5-5, Figure 3; and

Figures 6 and 7 are views similar to Figure 5 in which the frusto-conical stud of the spike is formed with a different number of certain splines, hereinafter fully described, than are formed upon the stud shown in Figure 5.

Referring to the annexed drawing in which the same parts are indicated by the same respective numbers in the several views, a shoe 1 has sole and heel parts 2 and 3, respectively, to which are applied a multiplicity of the improved spikes, as is illustrated in Figure 1.

In the drawing, the application of the improved spike is shown to the shoe heel 3, a retaining

member of the spike being embedded in the heel. This embedded retaining member comprises a square nut 4 seated in the exterior heel layer 6 and having a flange 5 which is confined between the heel layers 6 and 7, as clearly shown in Figure 2. The nuts 4 are first seated in suitable holes formed in the outer heel layer 6 and then the layer 6 secured to the layer 7 with the flanges 5 securely confined therebetween.

10 The spike is secured to the nut 4 by means of an exteriorly threaded end of a stem 11. The opposite end of the spike is a cone shaped formation having the ground-engaging terminal portion 8 and a plurality of downwardly-converging spaced longitudinal recesses forming a number of spaced exterior lengthwise-extending downwardly-tapered splines or flutes 9 having downwardly-converging side walls, four such splines 9 being shown in Figures 3 and 5 whose downward projection is inwardly toward the longitudinal axis of the stud, said splines alternating with the downwardly-converging recesses. The inner or upper ends of the splines 9 merge into a flange or base 10 from the upper surface of which the threaded stem 11 extends. The inner or bottom cylindrical part 11¹ of the stem 11 is plain. A washer 12 loosely surrounds the inner unthreaded part 11¹ of the stem 11 and seats against the outer face of the shoe sole or heel, this washer 12 being of strengthened formation as illustrated by the corrugated part 13 thereof.

The washer 12 is applied before the stem 11 is formed with a thread. This is effected by passing the washer 12 over the unthreaded stem 11 and then cold rolling the thread on the stem 11, the thread being of slightly greater diameter than the hole 12¹ in the washer 12 so that after the thread is formed the washer 12 is retained by the threaded stem 11.

40 The depth of the unthreaded part 11¹ of the stem 11 is somewhat greater than the thickness of the washer 12, and the diameter of the hole 12¹ of the washer 12 is somewhat greater than the diameter of the cylindrical unthreaded part 11¹, so that the washer 12 is loose upon the part 11¹ and can also play somewhat lengthwise thereof to accommodate expansion and contraction of the heel layers 6 and 7 due to the effect of moisture or of a drying out thereof.

50 In the form of the device shown in Figure 6, the splines 18 of the stud 17 are three in number, and in Figure 7 the splines 20 of the stud 19 are six in number.

The splines 9 provide means for securely gripping the stud 8 by the jaw 16 of a tool 15, which

jaw 16 has complementary parts engaging the recessed portions of the stud 8 between the splines 9, thereby permitting very positive application of the spike to the nut 4. Also, the spike can be readily removed from the nut 4 by the tool 15 when it is desired to replace the spike. These spikes are exposed to rough usage and ordinarily should be replaced several times during the lifetime of a shoe so that the spline formation of the spike and the use of a tool complementary thereto to provide convenient means for the frequent application and removal of the spikes and also provide that the application thereof can be made very positively to secure a solid seating of the same and also to provide a positive and convenient removal thereof.

An important further advantage of the splined shoe spike is that this formation readily pierces the ground of hard golf fairways and prevents lateral or sidewise movement of the golf shoe thereon, thereby reducing slippage to a minimum.

What I claim is:

An integral metal shoe spike having a threaded shoe-engaging stem and an oppositely disposed cone-shaped stud, said stud having a plurality of spaced exterior lengthwise-extending splines, the latter having downwardly-converging side walls,

the downward projection of said splines being inwardly toward the longitudinal axis of the stud, said stud further having downwardly-converging recesses intermediate said splines, said spike having an enlarged flange intermediate the stem and stud, the upper ends of the splines merging into said enlarged flange.

ALFRED G. MERLIN.
